UNITED STATES PATENT OFFICE.

MATHEW B. MORGAN, OF CLEVELAND HEIGHTS, OHIO, ASSIGNOR TO THE CLEVELAND TRACTOR COMPANY, OF EUCLID, OHIO, A CORPORATION OF OHIO.

TRACK BELT.

Application filed July 22, 1920. Serial No. 398,262.

To all whom it may concern:

Be it known that I, MATHEW B. MORGAN, a citizen of the United States, residing at Cleveland Heights, in the county of Cuyahoga and State of Ohio, have invented a certain new and useful Improvement in Track Belts, of which the following is a full, clear, and exact description.

The object of this invention is to provide, for use on track laying tractors, a strong, serviceable track belt comprising a plurality of pivoted together links made from pressed steel parts.

The invention consists in the construction and combination of parts shown in the drawing and hereinafter described and pointed out definitely in the appended claims.

In the drawing, Fig. 1 is a plan view of a short section of the track belt comprising three pivoted together links, the top plates of two of said links being partially broken away and the parts below said top plates being shown in horizontal section through the axis of the joint between the two links. Fig. 2 is a sectional side elevation in the plane indicated by line 2—2 on Fig. 1; Fig. 3 is an end view of one of the A-type links; Figs. 4, 5 and 6 show the construction of the track members employed on links of the A-type; Fig. 4 being a plan view partly broken away and sectioned; Fig. 5 a side elevation looking into the open end of said track member, and Fig. 6 being a vertical section in the plane of line 6—6 on Fig. 4. Figs. 7, 8 and

9 show the construction of the track members employed on links of the B-type; Fig. 7 being a plan view partly broken away and sectioned, Fig. 8 a side elevation looking into the open end of said member, and Fig. 9 a transverse vertical section in the plane of line 9—9 on Fig. 7.

A track belt constructed according to this invention is made up of alternately placed links A and B which have many features in common, but which also differ in certain respects, as will be hereinafter pointed out. Each link includes in its construction two track members, which are arranged side by side and are connected together, each of said track members having parallel horizontal top and bottom portions, of which the former serve as parts of the track or rail for wheels or rollers mounted on the tractor. Each link as shown, also includes a bottom plate or shoe 10, to which the track mem-

bers are secured by bolts 12 or other suitable means. This shoe adds to the practical value of the construction; but if it were omitted the respective links could be operatively connected by the means shown, and the resulting track belt would be operative for some purposes.

The track members which form parts of links A are indicated by 20, and those which form parts of links B are indicated by 20^a, and the two track members 20 employed on an A link may be exactly alike; and so may the two track members 20^a of each B link.

The track members employed in the construction of both types of links are drawn down from a flat sheet metal blank into the form of a cup whose depth is substantially equal to one half the width of the shoe. Each of these cup-shaped members has a closed end 21 and two substantially parallel straight sides 22, 23, which become respectively the top and bottom of the track member when it is secured upon the shoe.

These top and bottom members 22, 23, which are parts of both the A and B links, are connected at both ends by two integral straps, the combined width of which equals the width of the track member from the closed to the open end thereof.

The differences between the two links A and B are produced by the differences in the construction and arrangement of these strap members with respect to the closed and open ends of the track member of which they are parts.

These straps 24 on the track members 20 and the straps 24^a on the track members 20^a are bent outwardly, i. e., away from each other into U-shape; but the two straps 25 on the track members 20 as well as the two straps 25^a on track members 20^a are reversely curved, that is, they are bent toward each other. The width of the U-shaped straps 24 on each track member 20 is the same as that of the reversely curved straps 25^a on each track member 20^a. Likewise the width of the U-shaped straps 24^a on track members 20^a is the same as the width of the reversely curved straps 25 on the track members 20. On the track members 20 associated with the A links, the U-shaped straps 24 are adjacent the open sides of the members and the reversely curved straps 25 are adjacent the closed sides of said members. But on the track members 20^a associated with the

B links, the U-shaped straps 24^a are adjacent the closed ends of said members, while the reversely curved straps 25^a are adjacent the open sides of the members 20^a.

- 5 To construct one of the A links as shown, two track members 20 are secured upon the bottom plate or shoe with their closed ends in contact along the longitudinal central line of the shoe. To produce one of the B links 10 two track members 20^a are secured to the shoe with their closed ends in contact along the longitudinal central line of said shoe.

To connect an A and a B link together in the process of producing a track belt, the 15 U-shaped straps 24^a on the B link are inserted between the two U-shaped straps 24 which are parts of the A link. The outer surface of the straps 24^a fit against the outer surfaces of the reversely bent straps 25 on link A; and likewise the outer surfaces of the straps 24 engage with and fit the reversely curved straps 25^a on the B link. When the parts are in this position the pintle pin is passed through the eye formed by the 25 U-shaped straps 24 located near the edges of the A links and the U-shaped straps 24^a forming parts of the B link and located at the center thereof. These pintle pins also pass through and fit in holes 29 which are 30 formed in the closed ends of the cup-shaped track members 20^a.

The middle parts of the top members 23 of the pivoted together links are in the same plane and serve as tracks to support the track 35 wheels of the tractor, which of course are not shown in the drawing. This central track surface on all of the links is depressed slightly below those parts of the top members 21 which are adjacent the sides of the link.

- 40 The track belt as shown is especially intended for use in connection with double sprocket wheeels, that is to say, sprocket wheels each having two separated sprocket teeth carrying disks. In order that the teeth 45 of these sprockets may engage the pins and thereby drive an endless track belt made of the described links slots 30 are formed through the tops of the track members, and are continued into the strap loops as far 50 as necessary, substantially as shown.

Having described my invention I claim:

1. A track belt unit comprising two similar cup-shaped members having horizontal top and bottom portions placed side by side 55 and secured together, the adjacent inner portions of said horizontal top portions being in a lower horizontal plane than the outer portions thereof forming a longitudinal roller guideway centrally of said unit.
- 60 2. A track belt unit comprising two similar cup-shaped members having horizontal top and bottom portions placed side by side and closed ends secured together, said horizontal top portions being formed to abut 65 each other and provide a longitudinal roller

bearing surface centrally of said unit, and a shoe on which said members are secured.

3. A track belt unit comprising two cup-shaped members which are closed at one side and open at the other side and have 70 substantially horizontal top and bottom portions, said two members being secured together with their closed ends in contact, and a shoe to which said members are secured.

4. A track belt unit comprising two similar track units placed side by side, in contact, and secured together to form one part of a link structure, each of said track members having a top and bottom portion, the said top and bottom portions at both ends of 80 the link being connected by portions which have outwardly bent U-shaped surfaces and by portions which have reversely curved surfaces.

5. A track belt unit comprising two similar track units placed side by side, in contact, and secured together to form one part of a link structure, each of said track members having a top and bottom portion, the said top and bottom portions at both ends of the 90 link being connected by portions which have outwardly bent U-shaped surfaces and by portions which have reversely curved surfaces, and a pintle pin passing through the eye formed by the overlapping ends of the 95 U-shaped surfaces on adjacent members.

6. A track belt comprising a plurality of pivoted together links, each comprising a shoe, and two flat cup-shaped track members which are secured upon said shoe with 100 their closed ends in substantial contact along the longitudinal central line of said shoe, each of said track members having substantially parallel and horizontal top and bottom portions, and, at each end of said member, an outwardly bent U-shaped strap loop and a reversely curved strap both of which connect said top and bottom portions and are integral parts of them.

7. A track belt comprising a plurality of 110 pivoted together links, each comprising a shoe, and two flat cup-shaped track members which are secured upon said shoe with their closed ends in substantial contact along the longitudinal central line of said shoe, 115 each of said track members having substantially parallel and horizontal top and bottom portions, and, at each end of said member, an outwardly bent U-shaped strap loop and a reversely curved strap both of which connect said top and bottom portions and are integral parts of them, the outwardly bent 120 strap loops on every link being longitudinally aligned and in contact with the reversely curved straps on the contiguous 125 links, and pintle pins which go through the eyes formed by the overlapping outwardly bent strap loops on adjacent links.

8. A track belt comprising a plurality of pivoted together links each comprising a 130

- shoe and two flat cup-shaped track members which are secured upon said shoe with their closed ends in substantial contact along the longitudinal central line of said shoe each 5 of said track members having substantially parallel and horizontal top and bottom portions and at each end of said member an outwardly bent U-shaped strap loop and a reversely curved strap both of which connect 10 said top and bottom portions and are integral parts of them, the U-shaped outwardly bent strap loops on every other link being adjacent the open outer edges of the track members thereof and the outwardly 15 bent U-shaped strap loops on the intermediate links being located adjacent the closed inner ends of said track members, and the width of the outwardly bent strap loops on each link being substantially the same as the 20 reversely curved straps on the contiguous links.
9. A track belt comprising a plurality of pivoted together links, each comprising a shoe, and two flat cup-shaped track members 25 which are secured upon said shoe with their closed ends in substantial contact along the longitudinal central line of said shoe each of said track members having substantially parallel and horizontal top and bottom portions, and, at each end of said member, an 30 outwardly bent U-shaped strap loop and a reversely curved strap both of which connect said top and bottom portions and are integral parts of them, the outwardly bent strap loops on every link being longitudinally 35 aligned and in contact with the reversely curved strap on the next link, and pintle pins which go through the eyes formed by the overlapping outwardly bent strap loops on contiguous links, said track members being formed with narrow slots through them 40 to permit the passage of sprocket teeth into engagement with said pintle pins.
10. A track belt unit comprising two cup shaped members which are closed at one side 45 and open at the other side and are secured together with their closed ends in contact, said members having substantially horizontal top and bottom portions which abut each other, the horizontal top portions providing 50 a continuous longitudinal roller bearing surface.

In testimony whereof, I hereunto affix my signature.

MATHEW B. MORGAN.
